UNITED STATES PATENT OFFICE.

GEORGE S. SHAW, OF LOUISVILLE, KENTUCKY, ASSIGNOR TO LOUISVILLE FROG & SWITCH COMPANY, OF LOUISVILLE, KENTUCKY, A CORPORATION.

RAILWAY FROG.

1,402,098.

Specification of Letters Patent. Patented Jan. 3, 1922.

Application filed May 5, 1919. Serial No. 294,645.

To all whom it may concern:

Be it known that I, GEORGE S. SHAW, a citizen of the United States, and a resident of Louisville, county of Jefferson, and State of Kentucky, have invented certain new and useful Improvements in Railway-Frogs, of which the following is a specification.

The invention seeks to provide an improved railway frog having a body portion each end of which is adapted to align with a pair of rails of ordinary section and which is provided with arms to which such rails are secured, so that the ordinary track rails can be used for the rail arms of the frog and the necessity of grinding, machining or otherwise shaping special rail arms is avoided.

The invention further seeks to provide improved means for securing the rails or rail arms to the body of the frog which can be readily adjusted to take up any wear between the attached parts. With these and other objects in view, as shall presently appear, the invention consists in the features of improvement hereinafter set forth, illustrated in the preferred form in the accompanying drawing, and more particularly pointed out in the appended claims.

In the drawings: Figure 1 is a plan of the improved frog. Figs. 2, 3, 4 and 5 are cross sections on the lines 2-2, 3-3, 4-4 and 5-5 respectively of Fig. 1. Fig. 6 is a side elevation of the toe or forked end of the frog. Fig. 7 is a longitudinal section on the line 7-7 of Fig. 1. Fig. 8 is a view similar to Fig. 7, showing a modification.

The body *a* of the frog is formed of a single steel casting or forging having a height equal to the height of the rails for which it is designed. The heel end is of sufficient width to align with a pair of rails of ordinary T-section and is preferably provided with a single head 1 having edge flanges or gauge facings 2 which are adapted to align with the gauge sides of the heads of a pair of rails *b*. The heel end is also provided with a wedge shaped integral arm 3, having outwardly divergent side walls, which extends between and is adapted to fit snugly against the inner adjacent sides of the rails *b*. The greater portion of the upper face of the arm 3 is preferably located in the same plane with the head 1 of the frog, but the other end portion is preferably downwardly inclined, as indicated by the shad-

ing in Fig. 1. A series of fastener bolts 4 extends transversely through the ends of the rails and arm 3 to securely clamp the rails to the body of the frog. The connection between the rails *b* and the body of the frog is also preferably strengthened by joint plates or angle bars 5 which fit against the outer sides of the rails between the heads and base flanges thereof and are secured thereto by the bolts 4. The heel end of the frog body is preferably provided with base flanges 6 which align with the base flanges of the rails *b*. The heel of the frog body is reduced in thickness between the gauge and base flanges 2 and 6 so as to substantially align with the outer side faces of the rails *b* and properly receive the inner ends of the strengthening bars 5 which are secured to the frog body by transverse through bolts 7. As usual, the head 1 extends to and slightly beyond the center of the body of the frog and tapers to a point 8.

The opposite end or toe of the body of the frog is provided with spaced heads 9 on opposite sides of a groove 10, and is of sufficient width to align with a pair of rails *c* of ordinary T-section with the sides or gauge facings of the groove 10 in alignment with the gauge sides of the rail heads. At this end the frog body is also provided with a pair of integral spaced arms 11 which fit the outer sides of the rails *c* and the upper faces of which are preferably located in the same plane with the upper faces of the heads 9 and also of the rail heads, although the outer portion of the upper faces of these arms are preferably inclined, as indicated by the shading in Fig. 1. A throat block or blocks is interposed between the inner ends of the rails *c* and bolts clamp the ends of the rails between the arms 11 and the throat block or blocks. In the present improved construction, inner and outer wedge-shaped throat blocks 12 and 13, which fit snugly against the adjacent side faces of the rail *c*, are provided, the inner throat block being adjustable to take up any wear between the rails *c* and the arms 11 of the frog body. Preferably, the inner adjustable throat block is longer and has a greater bearing on the rails *c* than the outer block 13, and the blocks are held in position by transverse through bolts 14, the ends of which extend through the rails *c* and integral arms 11 of the frog body. As shown in Fig. 7, the bolt-hole through the

outer throat block is round, so that it is held fixed or rigid in position by the outer bolt 14. But the bolt-holes through the inner block 12 are elongated so that this block can be 5 adjusted toward the body of the frog, so that by its wedge-like action it can readily take up wear between the rails *c* and the arms 11 of the frog body. To securely hold the throat block 12 in adjustable position, 10 suitable spacing devices are provided between its outer end and the outer throat block 13 which, as stated, is rigidly held in fixed position. The spacing devices referred to can be varied.

15 As indicated in Fig. 7, the adjacent faces of the blocks 12 and 13 are provided with aligned sockets for receiving a pin 15 and a washer 16 on the pin holds the blocks in the desired spaced relation. When the frog 20 is first installed, the wedge-shaped throat blocks 12 and 13 are inserted between the rails with a relatively thin washer 16 between them. The through bolts 14 are inserted and the nut through the outer block 25 is first tightened, then by tightening the nuts on the other bolts 14 the parts at the toe or forked end of the frog are drawn into rigid working position, with the rails *c* firmly clamped between the throat blocks 30 and the integral arms 11 of the frog body.

If any of the parts become worn, so that the contact between the rails and the arms 11 is loosened, the outer block 13 can be removed and the nuts on the bolts through the 35 inner adjustable block 12 loosened so that the latter can be driven forward to a firm wedging position. Then by placing a thicker or an additional washer upon the pin 15 and replacing the outer wedge block the inner 40 adjustable wedge block will be firmly held in adjusted position, and by re-tightening all the nuts, the rigidity of the connection can be readily renewed.

In the modification indicated in Fig. 8, the 45 spacing device between the fixed and adjustable throat blocks is in the form of an adjusting screw, the end portions 17 of which are preferably provided with right and left hand threads respectively, and engage correspondingly threaded sockets in the adjacent ends of the blocks. The enlarged central portion 18 of the spacing screw is shaped to receive a suitable spanner. In this form the inner block can be adjusted 50 without removing the outer block.

The base flange 6 of the body of the frog preferably extends throughout the entire length of the body of the frog and also throughout the length of the integral arms 60 11 at the toe or forked end of the frog. The outer side face of one of the arms 11 immediately above the flange 6 is provided with squared integral fillets or bosses 19 which are arranged beneath the bolt-holes 65 of the arm and are adapted to engage the

heads of the bolts 14. The bolts are thereby held against turning when the nuts thereof are tightened or loosened, and the necessity of employing other devices for holding the bolts against turning is thereby avoided. 70

To strengthen the integral arms 11 at the juncture thereof with the main body of the frog, reinforcing bars or fish-plates 20 can be secured against the outer side faces of the arms and secured thereto by means of the 75 through bolts 14 which also serve to clamp the pair of rails *c* to the arms. Where such reinforcing bars are employed, the side faces of the frog body adjacent its toe are shaped to receive them and the body of the frog is 80 provided with bolt-holes for receiving a series of bolts 21 that secure the inner ends of the reinforcing bars 20 to the frog body.

The heads 9 at the toe of the frog are of considerable width and the gauge edges or facings thereof taper inwardly toward the center of the frog and merge into the wheel-guard facings 22 which extend on opposite sides of and parallel to the faces of the point 8, being separated therefrom by 90 grooves 23. The grooves and wheel-guard facings preferably extend to some distance beyond the point and are provided with widened ends or throats 24. The outer faces 95 of the heads 9 taper inwardly toward the center of the frog body and thence flare outwardly, as shown. The construction thus affords broad, flat wheel treads on the portion of the frog body having the guard faces 22 and which faces serve to guide the guard 100 wheels to the proper groove on opposite sides of the frog point. By reason of this construction the shock and jar to the frog, occasioned by heavy engine wheels or worn car-wheels, is materially reduced. 105

The main body of the frog is hollow to reduce weight and is provided at intervals with transverse strengthening flanges 26 and also with thickened portions or flanges 27 through which the holes for the bolts 4, 7 11 and 21 extend.

Obviously, changes may be made in the details set forth without departure from the essentials of the invention as defined by the claims. 115

I claim as my invention.

1. A railway frog comprising a body having each end adapted to align with a pair of rail ends of ordinary full cross section and provided at its ends with integral extensions or arms having tread surfaces and adapted to fit against the sides of the rails and be secured thereto, substantially as described. 120

2. In a railway frog, a hollow body portion provided with base flanges and having each end adapted to align with a pair of rail ends of ordinary full cross section, said body having an integral arm at one end adapted to fit between one pair of rails, and 125

a pair of integral spaced arms at the opposite end adapted to fit against the outer faces of the other pair of rails, a throat block adapted to fit between the latter pair of rails, and through bolts for securing the rails to said arms and for holding said throat block in position, substantially as described.

3. In a railway frog, a body portion having each end adapted to align with a pair of rail ends of ordinary section, said body having an integral arm at one end adapted to fit between one pair of rails, and a pair of integral spaced arms at the opposite end adapted to fit against the outer faces of the other pair of rails, a throat block adapted to fit between the latter pair of rails, through bolts for securing said rails to said arms and for holding said throat block in position, reinforcing bars engaging the ends of said bolts and overlapping the ends of said body portion, and through bolts for securing said bars to said body, substantially as described.

4. In a railway frog, a body having an integral extension at its heel end adapted to fit between a pair of rails and a pair of integral arms at its opposite end adapted to fit the outer side faces of a second pair of rails, joint bars and through bolts for securing one pair of rails to said extension and to the adjacent end of said body, and a throat block and through bolts for securing the other pair of rails to said spaced arms, substantially as described.

5. A railway frog having spaced heads at one end adapted to align with a pair of rail ends of ordinary full cross section and integral spaced arms provided with tread surfaces and arranged to fit against the outer side faces of the rails, a wedge-shaped throat block adapted to fit between the pair of rails, and bolts extending through said arms and throat block for securing the rails to the frog, substantially as described.

6. A railway frog having spaced heads at one end adapted to align with a pair of rail ends of ordinary section and integral spaced arms arranged to fit against the outer side faces of the rails, a wedge-shaped throat block adapted to fit between the pair

of rails, bolts extending through said arms and throat block for clamping the rails thereto, reinforcing bars engaging the ends of said bolts and overlapping the body portion of the frog, and bolts extending through said bars and body portion, substantially as described.

7. A railway frog having a pair of spaced heads and a pair of integral spaced arms at one end adapted, respectively, to align with and fit against the outer side faces of a pair of rail ends of ordinary full cross section, an adjustable wedge-shaped throat block adapted to fit between the rail ends, and through bolts for securing the rails to said arms and for holding said adjustable throat block in position, substantially as described.

8. A railway frog having spaced heads at one end adapted to align with a pair of rail ends of ordinary section and integral spaced arms arranged to fit against the outer side faces of the rails, a wedge-shaped throat block adapted to fit between the pair of rails, and bolts extending through said arms and throat block for securing the rails to the frog, one of said arms having integral lugs for engaging the heads of said bolts, substantially as described.

9. A railway frog having a pair of spaced arms at one end adapted to overlap the end portions of a pair of rails, inner and outer wedge-shaped throat blocks adapted to fit between the rails, spacing devices between said blocks, and fastening means for clamping the rails between said arms and throat blocks arranged to hold the outer block in fixed position and permit the adjustment of the inner block, substantially as described.

10. A railway frog having a pair of spaced arms at one end adapted to overlap the end portions of a pair of rails, inner and outer wedge-shaped throat blocks adapted to fit between the rails, spacing devices between said blocks, and bolts extending through the arms, rails and throat blocks and arranged to hold the outer block fixed and permit the adjustment of the inner block, substantially as described.

GEORGE S. SHAW.
